UNITED STATES PATENT OFFICE.

EDWARD P. BULLARD, JR., OF BRIDGEPORT, CONNECTICUT.

CUTTING-LUBRICANT ATTACHMENT FOR MACHINE-TOOLS.

1,076,947.

Specification of Letters Patent.

Patented Oct. 28, 1913.

Application filed February 12, 1912. Serial No. 677,246.

To all whom it may concern:

Be it known that I, EDWARD P. BULLARD, Jr., citizen of the United States, and resident of Bridgeport, in the county of Fairfield and State of Connecticut, have invented certain new and useful Improvements in Cutting-Lubricant Attachments for Machine-Tools, of which the following is a specification.

10 This invention relates to improvements in machine tools such for instance as turret lathes, boring mills, and like machines employing a rotary work carrying table, and it refers particularly to a lubricant attachment for such styles of machines whereby a stream of water or other cutting lubricant may be made to flow upon the cutting tools while in operation.

15 The purpose of the invention is to provide a practical and efficient form of lubricant attachment whereby an abundant supply of lubricant can be automatically supplied to the cutting tools in a way to keep them cool and in good repair thus prolonging their life and usefulness; to so construct the apparatus that the same lubricant can be used over and over again through a circulating medium which is connected to be operated by the machine to which it is applied, and to particularly design the device so that the bearings will be properly protected from the water or other kind of cutting lubricant; and finally to provide a lubricant attachment for the above purpose which can be readily applied to standard makes of machine tools of the before mentioned class without the necessity of particularly designing them for the purpose.

20 Upon the accompanying three sheets of drawings forming a part of this specification, similar characters of reference will be found to designate like or corresponding parts throughout the several figures, and upon which,

25 Figure 1, shows a plan view of a portion of a mill of the class specified and including a rotary work carrying table with my improved lubricant attachment applied thereto. Fig. 2, is a detail vertical cross section taken through the rotary table and connected parts on line 2—2 of Fig. 1. Fig. 3, is a similar detail cross section taken on line 3—3 of Fig. 1. Fig. 4, is a front elevation partly broken away of the mechanism shown in Fig. 1. Fig. 5, is an enlarged central vertical sectional view taken on line

5—5 of Fig. 4 showing an adjustable manifold through which the cutting lubricant is supplied to the cutting tools. Fig. 6, is a central vertical sectional view through the 60 table and lubricant attachment taken on line 6—6 of Fig. 1, and, Fig. 7, is a further detail vertical sectional view taken through the edge portion of the table and its connected parts taken on line 7—7 of Fig. 1. 65

Referring in detail to the characters of reference marked upon the drawings 10 represents a portion of the frame or uprights of the machine, and 11 the bed portion of the same for supporting the rotary table 12, 70 said table being provided with a spindle 13 that is properly journaled in bearings 14 of said bed. The table is provided with an annular beveled gear 15 by means of which it is made to rotate upon its bearing in the 75 usual or any preferred manner.

16 represents a turret head for carrying the central operating cutting tools 17.

18 represents a side head that is suitably supported from the frame work of the machine and is designed to carry tools 19 that also operate upon the work, not shown, carried by the table in the usual or any preferred manner. The said table is also provided with radial slots for the attachment 85 of clamping jaws, not shown, to secure the work upon the table to be operated upon by the several tools, either single, or jointly, as desired.

20 represents an annular ring that is 90 tightly secured to the lower peripheral edge portion of the rotary table in a manner to turn therewith, and includes an annular depending flange 21 over which the flow of lubricant from the table is to be deflected. 95 A second and special shaped ring 22 is located beneath the before mentioned ring and is supported upon the top edge of the base 11 by means of screws as shown in Figs. 1 and 2. This ring is provided in its top side 100 with a central annular groove 23, an inner annular groove 24, and an outer groove or shoulder 25. The latter does not constitute a complete annular groove since the outer edge is cut away as at 26 upon the front side 105 of the base, while upon the inner or rear sides it is extended up to form a flange 27 for the attachment of the inner semi-circular shaped shield 28. An annular rib 29 on the under side of the table, operates in the inner 110 annular groove 24 in a way to form a bearing, while the flange 21 of the ring 20 be-

fore mentioned similarly operates in the shoulder and groove 25 of the lower ring 22. A series of oblong holes 30 are formed through the bottom of the central groove 23 of the front portion of the ring 22 as is clearly shown in Figs. 1, 2, 6 and 7 so as to form a drainage therethrough into the semi-circular trough 31 which is secured to the front side of the table base. This trough is considerably wider at one end than at the other as will be seen from Fig. 1 and practically covers the front edge portion of the table and base. The said trough is secured to the base by means of bolts 32 and extends from the point 33 shown in Fig. 1, around the front of the machine to and including the discharge opening 34 located at the left. The bottom of this trough is preferably formed upon a slight decline to insure the drainage of the lubricant therein toward the said outlet 34 from whence it is discharged into the strainer 35 which is employed to separate the chips from the lubricant. The lubricant drains through this strainer into the settling pan 36 which has an overflow outlet 37 to permit the lubricant to pass out and down into the reservoir 38. The finer particles of metal which pass through the strainer are thus allowed to settle in the pan while the lubricant readily flows on out and into the reservoir.

A front shield 39 is connected to the end of the inner shield 28 at the point 33 and is secured to the before mentioned outer edge portion of the trough 31 by means of brackets 40, while a further and specially formed shield 41 is similarly attached to the edge portion of the trough around the discharge opening; and is connected in the rear with the opposite end of the before mentioned rear shield 28. A comparatively high shield is thus formed all around the table in a way to catch all of the chips and lubricant as they are thrown over the annular edge of the table and to direct the same down upon the ring 20 carried by the table and from which they are thrown off into the trough. The chips are obviously removed from the trough by the operator, while the lubricant runs down from the annular drain into the reservoir. In practice I have found that the lubricant had a tendency to work up under the flange 21 of the ring 20 and from thence on in to the table bearing; therefore the before mentioned central annular groove 23 was formed with its elongated openings 26 which I find thoroughly drain all the lubricant which may work in under the said flange 21, and thereby it insures a perfect protection to the bearing from the cutting lubricant.

Within the reservoir 38 is located a pump 42 which is driven through a pulley 43 operatively connected with any suitable part 65 of the machine to force the lubricant from

the reservoir up through the pipe 44 and into the manifold chamber 45 attached to the front of the base of the machine as shown in Fig. 4. From this chamber is formed two adjustable pipe connections 46 and 47 that are alike in construction, and are designed to convey a supply of cutting lubricant from the manifold chamber to the tools located at different points over the table as will be apparent from Figs. 1 and 4. The said adjustable pipe connections being similar in construction and operation, it will obviously be necessary to describe but one in detail.

Referring therefore to Figs. 4 and 5 it will be seen that two vertically disposed sleeves 48 are mounted in the top end of the manifold chamber and are designed to clamp the outer or larger tubes 49 in their vertically adjusted positions. The upper ends of these sleeves are slotted and provided with clamping screws 50 whereby the opposite side portions of the upper end of the clamps are made to bear upon the pipes and support them where desired. The inner pipes 51 are slidably mounted in the larger or outer pipes and are designed to be secured by means of a somewhat similar clamping device 52 which is operated by a screw and designated to clamp the split upper ends of the outer pipes against the periphery of the inner pipes so as to support the same in an extended position as shown in Figs. 4 and 5. To the upper ends of the inner pipes is connected an elbow and an inwardly disposed pipe 53, having a valve 54 therein for turning on and off the supply. In addition to the vertical adjustment provided for these pipes they are also rotatably mounted in the chamber to permit the arm 53 to be swung back and forth across the top of the table to line up with the cutting tools or out to one side against the front shield 39 as shown in dotted lines in Fig. 1.

Having thus described my invention what I claim and desire to secure by Letters Patent is:—

1. In a cutting lubricant attachment for machine tools, the combination with a rotary work carrying table, of a reservoir, a pump and pipe connections for circulating the lubricant from the reservoir to the table, and an annular drain surrounding the table to catch the lubricant and direct it back into the reservoir.

2. In a lubricant attachment for machine tools, the combination with a rotary work carrying table, of a reservoir, a pump and pipe connections for circulating the lubricant from the reservoir to the table, a manifold chamber within the pipe connections, and an annular drain surrounding the table to catch the lubricant and direct it back into the reservoir.

3. In a lubricant attachment for machine tools, the combination with a rotary table, of an annular ring secured thereto, a stationary grooved ring beneath the said annular ring and against which the annular ring operates, a trough to catch the lubricant as it flows from the said annular rings, a reservoir, and means for feeding the said lubricant to the table. 35
- 10 4. In a lubricant attachment for machine tools, the combination with a rotary table, of an annular ring secured thereto, a stationary grooved ring beneath the said annular ring and against which the annular ring 40 operates, a trough to catch the said lubricant as it flows from the said annular rings, a reservoir and means for feeding the lubricant to the said table, and a shield extending upward from the rings and trough to deflect the lubricant and chips into the trough. 45
- 15 5. In a lubricant attachment for machine tools, the combination with a rotary table, of an annular ring secured thereto, a stationary grooved ring beneath the said annular ring and having outlet holes from the said grooves, a trough to catch the said lubricant as it flows from the said holes, a reservoir and means for feeding the said lubricant to the table. 50
- 20 6. In a lubricant attachment for machine tools, the combination with a rotary table, of a ring secured to the said table and having an annular depending flange, a stationary perforated ring beneath and against 55 which the flanged ring operates, a trough to catch the lubricant from the openings of the stationary ring, a reservoir, and means to circulate the lubricant and feed it back upon the table. 60
- 25 7. In a lubricant attachment for machine tools, the combination with a rotary table, of a ring secured to the said table and having an annular depending flange, a stationary 65 perforated ring beneath and against which the flanged ring operates, a trough to catch the lubricant from the openings of the stationary ring, a reservoir, and means to circulate the lubricant and feed it back upon the table. 70
- 30 8. The combination with a rotary work carrying table of an attachment for feeding lubricant to the tools over the table and including a manifold chamber having an inlet, a pair of vertically and rotatably adjustable pipes mounted therein, and an attached lateral extension adapted to be swung across the top of the table. 75

Signed at Bridgeport in the county of Fairfield and State of Connecticut this 3rd day of Feby. A. D., 1912.
